(57) **CLAIM**

The ornamental design for a grommet, as shown and described.

DESCRIPTION

FIG. 1 is a top perspective view showing the new design; FIG. 2 is a front elevational view thereof, the front, rear, left side, and right side elevational views being identical; FIG. 3 is a top plan view thereof; and, FIG. 4 is a bottom plan view thereof.

The broken lines shown in FIGS. 3 and 4 are for the purpose of illustrating environment, and form no part of the claimed design.
